MAGNETIC TAPE CARTRIDGE

Helfried O. Rinkleib, Longmont, and Gary L. Switser,
Boulder, Colo., assignors to International Business
Machines Corporation, Armonk, N.Y.

Filed Nov. 30, 1973, Ser. No. 420,506

Term of patent 14 years

Int. Cl. D14—02, 99
U.S. Cl. D26—14 B

FIG. 1

FIG. 2

FIG. 3

FIG. 1 is a top perspective view of a magnetic tape cartridge showing our new design;

FIG. 2 is a bottom perspective view thereof; and

FIG. 3 is a cross-section taken on line 3—3 of FIG. 1.

We claim:

The ornamental design for a magnetic tape cartridge, substantially as shown and described.
